No. 694,662.

Patented Mar. 4, 1902.

W. S. PACA.

TELEPHONE EXCHANGE SIGNAL SYSTEM.

(Application filed May 7, 1901.)

(No Model.)

UNITED STATES PATENT OFFICE.

WILLIAM S. PACA, OF ERIE, PENNSYLVANIA, ASSIGNOR OF ONE-HALF TO
PETER H. ADAMS, OF ERIE, PENNSYLVANIA.

TELEPHONE-EXCHANGE SIGNAL SYSTEM.

SPECIFICATION forming part of Letters Patent No. 694,662, dated March 4, 1902.

Application filed May 7, 1901. Serial No. 59,129. (No model.)

To all whom it may concern:

Be it known that I, WILLIAM S. PACA, a citizen of the United States, residing at the city of Erie, in the county of Erie and State 5 of Pennsylvania, have invented certain new and useful Improvements in Telephone-Exchange Signal Systems; and I do hereby declare the following to be a full, clear, and exact description of the invention, such as will 10 enable others skilled in the art to which it appertains to make and use the same, reference being had to the accompanying drawings, and to the letters of reference marked thereon, forming part of this specification.

15 This invention relates to improvements in telephone-exchange signal systems, and has for its object the construction of exchange mechanism and telephone-circuits in such a manner that when a subscriber rings up the 20 exchange and removes his receiver from the hook and the operator inserts an answering-plug into the jack of the subscriber calling it operates to light an incandescent signal-lamp and when the subscriber called for removes his receiver from the hook it operates 25 to light a second incandescent lamp to approximately half-glow and at the same time reduces the first lamp lighted to half-glow, thereby indicating to the operator that the 30 subscriber called for has answered, and both of said lamps remain at such half-glow until the party calling and the party called for both hang their receivers upon their hooks, which operates to extinguish both lamps. 35 Thus the operator can at all times know when the party called for has answered and when both parties have finished their conversation without listening or verbally asking the parties whether they have finished their 40 conversation.

The features of this invention, the construction of the mechanism, and the arrangement of the circuits therein are hereinafter set forth and described, and illustrated in the 45 accompanying drawing, in which the figure is a diagrammatic drawing of an exchange mechanism and two subscribers' mechanisms embodying this invention.

In this drawing two subscribers' stations 50 are shown and distinguished as stations No.

1 and No. 2, and A A' are main-line circuits leading from station No. 1 to a drop B and a jack C on the exchange-switchboard, and D D' main-line circuits leading from station No. 2 to a drop B' and a jack C' on the switchboard, 55 and E E' are respectively operators' answer and call plugs connected by the usual flexible cords f f' and e⁴ e⁵ with the usual operator's switch F and through this switch to the operator's telephone E² and office-generator E³. The lines f f', leading from the answering-plugs, also connect directly through a relay H and thence by wire h to a battery B and ground G. The answer and call plugs E and E' are used interchangeably in the 60 jacks C and C', according to the station calling the exchange. The apparatus at each of the subscribers' stations consists of a magnetogenerator I, bell-magnets I', a transmitter J, a battery B', an induction-coil J', a 70 receiver K, and a hook-switch lever k of the usual construction. In wiring up the circuits of this apparatus, however, a ground G is provided, from which a wire g extends to a battery B and thence by wire g' to wire h o. 75 Now following the wire h it connects with the relay H and thence by wires f f' and branches f² and f³ to repeating-coil M M' and operator's switch F, and by continuation of lines f f' to contacts e e' on answering switch-plug 80 E, and thence, when the plug E is inserted into jack C by jack-body c and jack-tongue c', to main lines A A' and by branch lines b b' to drop-magnet B, and by continuation of the lines A A' by wires a a' to bell-magnets I', and by line k², leading from the wire joining the windings of the coils of the bell-magnet at a point approximately midway between said coils, to switch-contact k', operated by the heel of the switch-lever k when 90 the receiver K is removed therefrom, and thence by line k³ to ground G'. The reason for connecting the wire k', leading to ground G', with the bell-magnet coils in this manner is for the purpose of utilizing 95 the impedance of the bell-magnet coils and maintaining a perfect electrical balance of the circuit and to prevent the ground G' operating to produce induction and cross-talk on the circuit. This ground-circuit operates 100

to draw the armature H' of the relay H downward and close a switch-contact h' , which operates to close a circuit with a battery B^2 through a wire l , lamp L , wire l' , contact h' , wire l^2 , contacts h^2 , and wire l^3 , which operates to light the lamp L to a full glow, thus indicating the use of the caller's telephone. The operator then turns the portion F' of the switch F as indicated in dotted lines, connecting her telephone in circuit, and finds out the station the caller desires to be connected with. She then inserts the call-plug E' into the jack C' connected with the subscriber called for, which in the drawing is designated as "station No. 2." The operator then turns the part F^2 of the switch F , as shown in dotted lines therein, so as to connect the lines e^4 and e^5 with the branch lines e^6 and e^7 , leading to the office-generator, (not shown,) and rings up the subscriber called for in the usual manner, after which the parts F' F^2 of the switch F are returned to their normal positions, as indicated in full lines therein, and when the party called for removes his receiver K from the hook k a circuit is formed from the ground G by wire g , battery B , and wire g' to wire h o , and by wire o to and through relay O , and thence by lines m and m' to wires m^2 m^3 , and by branches m^4 and m^5 to repeating-coil $M M'$, and by continuation of lines m^2 and m^3 through the part F^2 of switch F , and by wires e^4 and e^5 to contacts e^2 and e^3 on the call-plug E' , and thence when the plug E' is inserted in the jack C' by jack-body c and jack-tongue c' to main lines $D D'$, and by branch lines b b' to drop-magnet B' , and by continuation of lines $D D'$ by wires a a' to bell-magnets I' and line K^2 to switch-contact k' , operated by the heel of the switch-lever k when the receiver K is removed therefrom, and thence by line k^3 to ground G' . The stations No. 1 and No. 2 are identical in their construction and arrangement of their circuits. This circuit then operates to draw the armature O' of the relay O downward, thereby operating the switch O^2 , which closes the contacts $R S$ and h^3 and simultaneously breaks the contact h^2 . This brings a lamp L' into circuit, and the circuit from the battery B^2 divides and passes into both lamps L and L' by wires l l' l^4 , contact h^3 , and wires l^5 , l^6 , and l^7 , but only lights and maintains the lamps L and L' at half-glow, which indicates to the operator that the lines from station No. 1 and No. 2 are connected and in use. The mechanism being in this position, the talking-circuit between stations Nos. 1 and 2, commencing at station No. 1, is by lines p p' , main lines $A A'$, thence through jack-body c and jack-tongue c' of jack C to contacts e e' on plug E , thence by lines f f' and branches f^2 f^3 to the part F' of the operator's switch F , thence by lines r and s to contacts $R S$, and thence by lines m^2 and m^3 to part F^2 of the operator's switch F , and thence by wires e^4 e^5 to contacts e^2 and e^3 on

plug E , and thence by jack-body c and jack-tongue c' of jack C' , by main lines D D' and lines p p' , to receiver K at station No. 2, and vice versa. This gives a direct talking-circuit without utilizing a repeating-coil $M M'$, but in case the operator switches in during a conversation and breaks the direct circuit at F' of the switch F the conversation can be continued through the repeating-coil $M M'$, and the same result is obtained in case of any derangement of the switch O^2 and the contacts R and S . It will be observed that while the lines a' connect with the lines p' , forming one side of the talking-circuit, and thence through wire a^3 , bell-coils I' , line k^2 , contact k' , and line k^3 with ground G' , yet the bell-coils I' , being wound with a resistance of approximately six hundred ohms, operate as impedance-coils and effectually prevent the passage of the high alternating voice-currents therethrough. When the parties at two stations—for example, stations No. 1 and No. 2—are connected, as hereinbefore described, should either party hang up his receiver K on the hook k the operation of the relays H and O will not in any wise be interfered with; but if both receivers K are returned to their hooks k then the relays H and O are cut out of circuit, and the circuits leading to the lamps L and L' being broken by the retraction of the armatures H' and O' are extinguished, thus clearly indicating to the operator that the parties connected have closed their conversation; but if the party at one of the stations connected—for example, the party at station No. 2—should hang up his receiver and the party at station No. 1 should leave the station and fail to return his receiver to the hook k and after a time the operator should desire to find out whether the parties were still using the line she can move the portion F' of the switch F so as to break the direct connection between relay H and relay O , and thence by battery B and ground G , thus releasing relay O and cutting-out lamp L' and causing lamp L to rise to full glow, thus indicating that the receiver at station No. 1 was not upon the hook K , and vice versa, if the receiver was off of the hook at station No. 2, the relay H would be released, cutting out lamp L and causing lamp L' to rise to full glow, thus in either case indicating which party had neglected to hang up his receiver, and if before the operator withdraws the plugs E and E' the party at station No. 1 desires another connection he removes his receiver K from the hook k , causing the lamp L to become lighted to full glow; but if, on the other hand, the party at station No. 2 desires to call before the plugs E E' have been withdrawn and removes his receiver K from the hook k' both of the lamps L and L' will be lighted to a half-glow. Thus the operator can readily know which of the stations desires another call and can thus ar-

range the answer and call plugs E and E' to respond thereto and call the party desired, as hereinbefore described.

I have thus shown diagrammatically and described an apparatus embodying two subscribers' stations and an exchange mechanism embodying my invention. It is obvious, however, that the jacks, answer and call plugs, and other portions of the exchange apparatus will be increased in number many times in the construction and operation of a telephone - exchange system, to correspond with the number of subscribers connected therewith. It is also obvious that many changes and modifications can be made in the construction and arrangement of the parts of the apparatus herein shown and described without departing from the spirit of my invention; therefore

20 What I claim as new, and desire to secure by Letters Patent of the United States, is—

1. In a telephone-exchange signal system, an exchange apparatus substantially comprising a battery, a lamp in circuit therewith, a relay for closing and opening said lamp-circuit, a battery connected with said relay and with a ground, and cord-circuits from said relay to a switch-plug, and a subscriber's-telephone-station apparatus, a wire leading from 25 between the bell-magnets of said station apparatus, and a switch adapted to connect said wire with a ground, substantially as set forth.

2. In a telephone-exchange signal system, an exchange apparatus substantially comprising a battery, lamps in circuits therewith, relays for closing and opening said lamp-circuits, a battery connected with said relays and with ground, a circuit leading from one relay to a repeating-coil, an operator's switch 30 and telephone and to an answering-plug, a circuit leading from another relay to a repeating-coil, an operator's switch and to a call-plug, subscribers'-telephone-station apparatus, a wire leading from the bell-magnets 35 of the station apparatus, a switch in the station apparatus adapted to connect said wire with ground-wires, and wires connecting said subscriber's-station apparatus with drop and jack mechanism on the exchange-switchboard, substantially as set forth.

3. In a telephone-exchange signal system, a switchboard substantially comprising jacks and drop mechanism, an operator's switch, a call apparatus, a repeating-coil, a battery, lamps in circuit therewith, relays operating switches for closing and opening said lamp-circuits, a battery connected with the relays and with a ground, wires leading from the relays to the repeating-coil, the operator's switch 40 and thence by branches to an operator's telephone and a calling apparatus, and continuations of said wires leading to answering and calling plugs adapted to operate in the jacks on said switchboard, subscribers'-telephone-station apparatus, wires leading from the bell-magnets of the station apparatus, switches

in the station apparatus adapted to connect said wires with ground-wires, and wires connecting said subscribers' stations with drop and jack mechanism on the exchange-switchboard, substantially as set forth. 70

4. In a telephone-exchange signal system, a switchboard, jacks, connecting-plugs, an operator's switch, a relay, switches operated by said relay, line-circuits from the connecting-plugs to the operator's switch and thence to the switches operated by the relay, and branches from said line-circuits connecting with the repeating-coil, substantially as set forth. 75

5. In a telephone-exchange signal system, a switchboard substantially comprising jack and drop mechanism, switch-plugs operating in the jacks, an operator's switch, an operator's telephone, a call apparatus, a repeating-coil, a switch, a relay operating the same, circuits leading from the switch-plugs to the operator's switch, and thence to the switch operated by the relay, and branch circuits from said circuits connecting with the repeating-coil, substantially as set forth. 80

6. In a telephone-exchange signal system, a switchboard substantially comprising jack and drop mechanism, switch-plugs operating in said jacks, an operator's switch, an operator's telephone, a call apparatus, a repeating-coil, switches, a relay for operating the same, circuits leading from the switch-plugs to the operator's switch and thence to the switch operated by the relay, branch circuits from 90 said circuits connecting with the repeating-coil, a battery, signal-lamps in circuit therewith, relays operating to open and close said lamp-circuits, a battery for operating said relays, and circuits from said relays to the 105 switch-plugs, substantially as set forth.

7. In a telephone-exchange signal system, a switchboard substantially comprising jack, switch-plug and drop mechanism, main-line circuits from subscribers' telephone-stations 110 connecting with said jacks and drop mechanism, an operator's switch, an operator's telephone, a call apparatus, a repeating-coil, a battery, lamps in circuit therewith, relays for closing and opening said lamp-circuits, 115 line-circuits from said switch-plugs to said relays, a switch in one of said line-circuits operated by one of said relays, a battery grounded at one side and connected with said relays on the other side, subscriber's-station apparatus connected with the main-line circuits leading to the jacks on the switchboard, a wire leading from the bell-magnets of each subscriber's-station apparatus to a switch therein adapted to connect such wire to 125 ground, substantially as set forth.

8. In a telephone-exchange signal system, a switchboard, jacks, switch-plugs, an operator's switch, a repeating-coil, relays, switches operated thereby, circuits leading from switch-plugs through the operator's switch to one of the relays and to the switches operated there- 130

by, and branches leading from said circuits to the repeating-coil, circuits leading from the other switch-plugs to the other relay, and branches leading from said circuits to the operator's switch and to the repeating-coil, and a battery and ground connected with said relays, substantially as set forth.

In testimony whereof I affix my signature in presence of two witnesses.
